UNITED STATES PATENT OFFICE.

LOUIS H. HOSEBEIN, OF CHICAGO, ILLINOIS, ASSIGNOR TO M. H. DETRICK CO., OF CHICAGO, ILLINOIS, A CORPORATION OF ILLINOIS.

FURNACE ARCH CONSTRUCTION.

Application filed March 26, 1918, Serial No. 224,749. Renewed May 9, 1921. Serial No. 468,047.

To all whom it may concern:

Be it known that I, LOUIS H. HOSEBEIN, a citizen of the United States, and resident of Chicago, in the county of Cook and State 5 of Illinois, have invented certain new and useful Improvements in Furnace Arch Constructions, of which the following is a specification.

This invention relates to that class of 10 furnace arch constructions wherein a series of fire bricks are supported by arch bars; having reference more especially to such constructions wherein an outer protective brick or bricks for the extremity of the 15 arch bar is or are detachably supported adjacent the end brick of the series.

The object of the present invention is to 20 provide a simple and efficient construction and organization of elements whereby the end brick of the series of bricks on the bar, is securely but detachably locked in place preparatory to the application of the outer protective brick or bricks to the structure.

To this end, my invention, generally 25 stated, consists in the combination with an arch bar, of a detachable end bracket therefor constituting, in effect, a continuation of the bar, said bracket being constructed to receive and support the end brick of the assembled series and having a member which 30 interlocks with the said brick in such a manner as to maintain the latter fixedly in position.

The invention also comprises such a construction wherein the said end brick is 35 adapted to receive and support a protective brick in close relation to the interlocking member and the adjacent end of the bracket.

The invention also comprises features of 40 construction which will be hereinafter described and claimed.

In the drawings—

Figure 1 is a perspective view of a portion of a furnace arch construction embodying 45 my invention, the protective end bricks being omitted.

Fig. 2 is an elevation of the detachable bracket and the adjacent end of the arch bar, showing the suspended bricks partly in section.

Fig. 3 is a vertical section, as on the line 3—3 of Fig. 2.

Figs. 4, 5 and 6 are perspective views, on a smaller scale, of different forms of bricks employed in the structure.

Referring to the drawings, 10 designates 55 an arch bar comprising a web having basal flanges 11 extending longitudinally thereof, which bar is carried by a suitable supporting structure of any usual or approved character.

The bar supports a series of counterpart 60 fire bricks 12, each of which has formed therein along its upper portion an undercut slot 13 of corresponding cross-section with the lower portion of the arch bar, whereby the bricks may be applied successively to the end of the bar and slid therealong so as to be supported in close contact 65 with each other.

14 designates a brick which is supported 70 at the rear of the series and constitutes, in effect, a part of the same. This brick is provided in a part of its upper portion with an undercut slot 15, which, instead of being applied directly to the basal flanges of the arch bar, is supported upon a flanged bracket extension 16 of special construction which is detachably secured to the end of the bar, as will presently appear. The brick 14 is 75 constructed and arranged to project partly beyond the bracket extension, the upper part of the outer projecting portion being cut away to form a depressed or hook-like seat 17 adjacent the undercut floor of the slot 15.

18 designates end protective bricks, each 80 having an upper overhanging portion 19 provided with a depending nose 20 adapted for registry with the depressed seat 17 of the brick 14. Thus the bricks 18 or any of them, can be readily applied to or removed 85 from the end brick 14. When the former bricks are so applied they are effectually supported and their upper portions protect the supporting bracket structure from the destructive action of the furnace heat.

The bracket structure, in its preferred 90 form, comprises a casting including a vertical web having an upper forward extension constituting a tongue 21 which is adapted to be fitted between a pair of spaced lugs 22 on the rear end of the arch bar and then be 95 detachably secured thereto by means, for example, of a wedge key 23 which is driven

through alining slots in the lugs and tongue respectively. The web is provided with a downward extension 24 having at its basal portion two oppositely-extending lateral flanges 25 the outer ends of which project somewhat beyond the rearward vertical edge of the web and terminate in an upstanding lug 26. The flanges 25 and lug 26 are so disposed in relation to each other that, preparatory to the application of the bracket structure to the end of the arch bar as just mentioned, the brick 14 can be slid upon the free ends of the flanges 25 in such a manner that the lug will enter the depressed seat portion of the brick 14 and thus span the adjacent end of the undercut portion of the slot 15 and serve as an effective end stop for the brick. The bracket with the brick 14 thus applied thereto being supported on the bar as stated, the brick thus has bearing against the adjacent brick 12 on the arch bar, and is embraced by and effectually locked between the latter brick and the lug 26.

By removing the key 23 the bracket together with the brick 14 can be readily detached in order to replace such brick with a new one, or to remove any or all of the series of bricks 12 from the arch bar, as need may require.

30 When the protective bricks 18 are applied to the end brick 14, the overhanging interlocking portions of the former cover the end lug 26 of the bracket structure and thus protect such lug as well as the adjacent parts of 35 the structure from the destructive action of the furnace heat. The arrangement is effective to prevent longitudinal displacement or creeping of the end brick 14 and the cover brick 18 in either direction. In the event the 40 bar 11 is arranged at an inclination downwardly from the end carrying the bracket, the creeping of the end brick 14 is prevented by the abutment of the cover brick 18 against the end of the lug 26. Likewise, if the bar 45 11 is inclined downwardly toward the bracket 24, the creeping of the end block 14 off of the bracket is prevented by the abutment afforded by the lug 26. While the terminal bricks are thus positively prevented 50 from displacement, they do not prevent the desirable freedom of relative movement of the several associated bricks induced by the changes in temperature.

I preferably provide the rear of the 55 bracket web with an upstanding portion bearing a horizontal shelf 27 adapted to sustain the bricks which constitute the apron wall of the furnace; the latter bricks thus being supported independently of the arch 60 bricks.

It is to be understood that my invention is not limited to the exact details of construction herein described as the same may be modified within the principle of the invention as defined in the appended claims.

I claim—

1. The combination with an arch bar and a series of fire bricks thereon, of means for locking an end brick at one end of the bar including an outwardly projecting portion terminating in an angularly-disposed lug constituting a locking member, said end brick having a slot therein which receives said projecting portion and having outwardly beyond the slot a reduced portion 70 into which said member extends, and a protective brick having a portion which overhangs the reduced portion of the said end brick.

2. The combination of a supporting bar, 80 a series of fire bricks thereon, an end bracket detachably mounted on said bar and having a brick-supporting portion extending longitudinally beyond the outer end of the body of the bracket and terminating in an angularly-disposed lug constituting a locking member, a brick having a slot therein which receives said supporting portion and having outwardly beyond the slot a bearing portion for said lug, and an end protective brick 90 supported in close relation to said slotted brick and lug.

3. The combination of a supporting bar, a series of fire bricks thereon, an end bracket detachably mounted on said bar and having 95 a brick-supporting portion extending longitudinally beyond the outer end of the body of the bracket and terminating in an angularly-disposed lug constituting a locking member, a brick having a slot therein constructed to receive the body of the bracket and its supporting portion and having outwardly beyond the slot a reduced portion 100 into which said lug extends, and an end protective brick having a portion interlocked with said reduced portion and confining the said lug.

4. The combination of a supporting bar, 110 a series of fire bricks thereon, an end bracket detachably mounted on said bar having lateral brick-supporting flanges extending endwise beyond the body of the bracket and terminating in an angularly-disposed locking lug, a brick having a slotted portion engaged by said flanges and lug and having a portion extending beyond said lug, and an end protective brick having an interlocking connection with the extended portion of the said slotted brick and confining the said lug. 115

5. The combination of a flanged supporting bar, a series of slotted fire bricks assembled thereon, an end bracket detachably mounted on said bar having a flange extending longitudinally beyond the outer end of the body of the bracket, said flange having an angularly-disposed lug constituting a locking member at its outer end, a slotted brick mounted on said bracket having an outwardly extending portion shaped to form a seat which receives the said retaining mem- 120 125 130

ber, and an end protective brick having an overhanging portion imposed on said seat in close relation to said member.

6. In an end bracket for arch bars, a body 5 having a basal brick-supporting flange extending longitudinally of and beyond one end of the body, the extension of said flange having at its outer end an up-standing brick-locking projection, and said body having 10 means whereby the bracket may be affixed to an arch bar.

7. In an end bracket for arch bars, a body having a basal brick-supporting flange extending longitudinally of and beyond one 15 end of the body, the extension of the flange having at its outer end an up-standing brick-locking projection, said body having an upper horizontal brick-supporting shelf and also means whereby the bracket may be 20 affixed to an arch bar.

8. In a furnace arch construction the combination of an arch bar, a plurality of bricks, movably suspended upon the bar in a series, the end of the bar being provided with a 25 stop effective upon the terminal brick to prevent its creeping in one direction, and one or more cover bricks supported on said terminal brick in position to cover the end portion of the bar and said stop and cooperating with the latter to prevent creeping of the terminal brick in the other direction.

9. In a furnace arch construction the combination with a brick supporting arch bar, of a terminal brick suspended thereon, a 35 cover brick suspended on the terminal brick in position to protect the end of the bar, and

a lug supported on the bar between said bricks in position to prevent their creeping in either direction on the bar, said lug being of less width than said terminal brick. 40

10. In a furnace arch construction the combination with an arch bar of a plurality of bricks suspended thereon in a series, said bar including a stop member cooperating with the terminal brick of the series to retain the same against displacement off the bar under pressure from the other bricks, said stop member being of less width than said terminal brick and a cover brick supported on said terminal brick in position to 50 protect said stop.

11. In a furnace arch construction the combination of an arch bar, a plurality of bricks suspended thereon, a bracket member detachably connected to the arch bar at one 55 end thereof, and a terminal brick retained by said bracket in cooperation with the bricks on the bar.

12. In a furnace arch construction the combination of an arch bar, a plurality of bricks suspended thereon in a series, a bracket having demountable connection with the arch bar at one end thereof, a plurality of bricks supported on said bracket, said bracket having a portion disposed for cooperation with the bricks supported thereon to prevent their displacement longitudinally of the bracket. 60

Signed at Chicago, in the county of Cook and State of Illinois, this 19th day of March A. D. 1918.

LOUIS H. HOSBEIN.
